UNITED STATES PATENT OFFICE

108,512

DESIGN FOR A CASING FOR UNIT HEATER OR SIMILAR ARTICLE

Clarence R. T. Hess, Prairie View, Ill., assignor
to Perfex Corporation, Milwaukee, Wis., a cor-
poration of Wisconsin

Application August 30, 1937, Serial No. 71,381

Term of patent 7 years

To all whom it may concern:

Be it known that I, Clarence R. T. Hess, a citizen
of the United States and a resident of Prairie
View, in the county of Lake and State of Illinois,
have invented a new, original, and ornamental
Design for a Casing for Unit Heater or Similar
Article, of which the following is a specification,
reference being had to the accompanying drawing,
forming a part thereof.

Figure 1 is a perspective view of a casing for
a unit heater or similar article showing the front,
bottom and one side of my new design, and

Figure 2 is a perspective view showing the front,
top and other side of the article.

The back of the casing is substantially plain
and has a circular opening therein.

I claim:

The ornamental design for a casing for unit
heater or similar article, substantially as shown
and described.

CLARENCE R. T. HESS.
